UNITED STATES PATENT OFFICE.

PAULINE LUTTMAN, OF ADAMSFORD, PENNSYLVANIA.

DESIGN FOR A MEMBER FOR GARMENT-FASTENERS.

SPECIFICATION forming part of Design No. 31,577, dated October 3, 1899.

Application filed May 22, 1899. Serial No. 717,848. Term of patent 7 years.

To all whom it may concern:

Be it known that I, PAULINE LUTTMAN, a citizen of the United States, residing at Adamsford, in the county of Delaware and State of Pennsylvania, have invented and produced a new and original Design for a Member for Garment-Fasteners, of which the following is a specification, reference being had to the accompanying drawing, forming part thereof.

The drawing shows a plan view of a member for a garment-fastener constructed in accordance with my invention.

As shown in the drawing, the leading or material feature of my design consists of a body *a*, which is substantially a right angle, one side of the angle being provided with perforations at its edge.

My invention comprises a right-angular blank having a vertically-disposed wing and a horizontally-disposed wing. The vertically-disposed wing is bounded by straight sides connected at their base by an arc, one side

of the vertically-disposed wing turned at right angles to itself to form the base of the horizontally-disposed wing, the upper side of which wing lies at an oblique angle to the base and is connected thereto at one end by an arc, the other end being connected with the remaining straight side of the vertically-disposed wing by an arc, the last-named side of the vertically-disposed wing being extended to a point beyond that at which the first-named side is turned at an angle. Perforations are distributed throughout the boundary of the horizontally-disposed wing.

Having thus described my invention, what I claim as new, and desire to secure by Letters Patent, is—

The design for a member for a garment-fastener, as herein shown and described.

PAULINE LUTTMAN.
